UNITED STATES PATENT OFFICE

JAMES S. RAGAINS, OF CALDWELL, IDAHO

FLUID-CURRENT MOTOR

Application filed December 7, 1929. Serial No. 412,450.

This invention relates to fluid current motors and has for its primary object to provide a motor of this character having an improved means for mounting paddles upon which the current acts in pairs so that when the same are brought into the path of flow of the current they will open out automatically into edge opposed relation to receive the full force of the current.

10 Another object of the invention is to provide an improved means whereby paddles mounted in pairs may swing to a side by side relation to feather through the fluid current during certain periods in the operation of 15 the motor.

Still another object of the invention is to provide a fluid current motor employing a plurality of paddles disposed between endless conveyor chains, wherein the paddle carrying portion of the structure may be adjusted with respect to the current to control the speed of operation of the motor.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

35 In the drawings:—

Figure 1 is a vertical longitudinal section through the motor embodying the present invention.

Figure 2 is a vertical transverse section.

40 Figure 3 is a sectional view taken transversely of a pair of paddles.

Figure 4 is a sectional view taken on the line 4—4 of Figure 3.

45 Figure 5 is a top plan view of a portion of the motor looking toward a pair of panels, partly being in section.

Figure 6 is a sectional view similar to Figure 3 showing the panels folded.

50 Referring more particularly to the drawings the numeral 1 indicates a supporting

structure for the motor embodying the present invention. This supporting structure may be of any approved design necessary for maintaining the motor in the proper position with respect to a moving current such for example as a stream of water, it consisting of a pair of upright beams 2 mounted upon suitable bases 3, cross connecting brace bars or struts 4 being disposed between the upright beams 2 in the manner shown.

Extending transversely of the beams 2 and suitably supported thereby for rotation is a shaft 5 one end of which extends beyond the supporting structure 1 in the manner shown for the support of a gear 6.

Oscillatably mounted upon the shaft 5 is a pair of beams 7 arranged in spaced parallel relation as shown, each of these beams being transversed by the shaft midway between its ends. At their ends the beams 7 are connected by shafts 8, these shafts 8 and the beams 7 making up the frame of the motor structure. The shafts 8 are each rotatably mounted and each carries adjacent each end a sprocket wheel 9. The wheels on one of the shafts 8 being connected with the sprocket wheels on the other of the shafts 8 by sprocket chains 10 which of course run the full length of the supporting beam 7 as shown.

One of the beams 7 has secured thereto a toothed segment 11 and mounted upon the upright beam 2 adjacent the toothed segment is a fixed lever 12 which carries the usual spring pressed pawl 13 which normally engages one of the teeth of the segment 11 to maintain the motor frame in adjusted position on the shaft 5.

At spaced intervals throughout each of the chains 10 are links 14 which have secured to their inner faces curved arms 15. Each of the arms is attached at one end to a link 14 in the manner shown so that it will be held rigidly in position, the other end of the arm having mounted thereon a stop 16.

Spaced from each of the links 14 of each chain are other specially formed links 17 the inner face of each of which is formed to provide two bearings 18 and 19. The bearings 18 and 19 are substantially in alignment trans-

versely of the chain with the free end of an arm 15.

Mounted between the two chains 10 between a pair of aligned bearings 18 is a flat 5 paddle 20 each end edge adjacent a longitudinal edge thereof being provided with a trunnion 21 for engagement in the adjacent bearing. Adjacent the other longitudinal edge and adjacent each end each paddle has 10 formed therethrough an elongated slot 22 through which the adjacent arm 15 extends so that as will be readily seen when the paddle swings inwardly it will swing along a pair of curved arms 15 and be brought to a 15 stop against the bodies 16 at the free ends of these arms in which position it will be at substantially right angles to the supporting chains and to the path of travel thereof.

Disposed between the chains 10 are a number 20 of frames of substantially cross-sectional design, each of which is indicated by the numeral 23. Each of these frames has a trunnion projecting from the end thereof as indicated at 24 in the corner between the 25 right angularly related faces, these trunnions 24 being oscillatably mounted in and between a pair of aligned bearings 19.

One of the right angularly related faces of each of the frames 19 is open while the other 30 thereof is closed by a panel 25 and these frames which will be hereinafter referred to as triangular paddles are so mounted on and between the chains 10 that the paneled side 25 may be brought into face opposed relation 35 with the adjacent flat paddle 20.

As will be understood the bars 15 are rigid with their supporting chain links so that those on one side of the structure will be directed oppositely from those on the other 40 side.

When the motor is in use it may be partially or completely submerged in a moving current as for example in a stream of water, it being so positioned that the free ends of 45 those arms 15 following below the shafts 8 will point in the direction in which the current flows. With the motor in this position the current will catch the paddles 20 and 23 at one end of the structure and swing them 50 to open position as shown, the paddles 20 swinging inwardly on their arms 15 while the triangular paddles 23 will swing to a position where the open side thereof will lie parallel with the chains and the panel 25 will 55 lie in a plane at right angles to the chain and in the same plane as the adjacent paddles 20. When each pair of paddles reaches the opposite end of the structure they will move about the sprocket wheels to the upper part 60 of the structure during which movement the paddles 20 will swing back to a position where their side faces will be parallel with the chains and the triangular paddles 23 will swing over to a position where their panels 65 25 will come into opposed relation with the

adjacent paddles 20 leaving the open sides of these elements extending outwardly from the chains so that no hindrance will be offered to the flow of the current during the idling movement of the paddles.

One of the sprocket wheel shafts 8 may be provided with a third sprocket wheel 26 to transmit power through the medium of a chain 27 to the center shaft 5 by means of a sprocket wheel 28 mounted thereon, this power being transferred from the center shaft through the gear 6 to any suitable power take-off mechanism.

From the foregoing description it will be readily seen that a fluid current motor constructed in accordance with the present invention may provide an economical and easily maintained source of power for performing various operations and due to the manner in which the paddles are mounted thereon and the manner in which the structure is supported the control of the power developed by the motor will be easy.

Having thus described my invention, what I claim is:

1. A fluid current motor, comprising a frame supporting a pair of spaced shafts, a pair of wheels on each of said shafts, endless connecting elements between the wheels of the shafts, spaced pairs of paddle elements pivotally mounted between said endless elements, one of the paddles of each pair being arranged to swing inwardly from the adjacent chain, the other being arranged to swing outwardly therefrom, a rigid guide element arranged at each end of and having sliding engagement with the inwardly swinging one of the paddles of each pair to limit the movement of its swing inwardly, and an open frame of triangular cross-sectional design carrying the other paddle of each pair for limiting its swinging movement during the operation of the motor.

2. A fluid current motor, comprising a frame supporting a pair of spaced shafts, a pair of wheels on each of said shafts, endless connecting elements between the wheels of the shafts, spaced pairs of paddle elements pivotally mounted between said endless elements, one of the paddles of each pair being arranged to swing inwardly from the adjacent chain, the other being arranged to swing outwardly therefrom, a rigid arcuate arm fixed to each endless element adjacent each end of the inwardly swinging paddle of each pair, each of said arms extending through a slot in the adjacent paddle and acting to guide the swinging movement of the same, a stop upon the other end of each of said arms to limit the swinging movement of the paddle thereon, and an open frame of triangular cross-section carrying the other paddle of each pair, said other paddle being disposed in one of the right angularly related sides of its supporting frame.

3. A fluid current motor, comprising a frame supporting a pair of spaced shafts, a pair of wheels on each of said shafts, endless connecting elements between the wheels of the shafts, spaced pairs of paddle elements pivotally mounted between said endless elements, one of the paddles of each pair being arranged to swing inwardly from the adjacent chain, the other being arranged to swing outwardly therefrom, a rigid arcuate arm fixed to each endless element adjacent each end of the inwardly swinging paddle of each pair, each of said arms extending through a slot in the adjacent paddle and acting to guide the swinging movement of the same, a stop upon the other end of each of said arms to limit the swinging movement of the paddle thereon, an open frame of triangular cross-section carrying the other paddle of each pair, said other paddle being disposed in one of the right angularly related sides of its supporting frame, and means for transmitting power from one of said endless element carrying wheels to a take-off element.
4. A fluid current motor comprising a supporting frame, a shaft carried by the frame, a motor frame comprising a pair of beams each pivotally mounted intermediate its ends upon said shaft and transverse shafts connecting the ends of said beams, a pair of sprocket wheels supported upon each of said transverse shafts, sprocket chains connecting the wheels on one of the transverse shafts with those on the other transverse shaft, arcuate arms secured at spaced intervals to each of said sprocket chains and extending inwardly thereof, and a paddle pivotally mounted between the sprocket chains adjacent each of said arms, each paddle having slots therein to receive the adjacent arms, said arms maintaining the paddles in a plane extending transversely of the chains during a period in the operation of the motor.
5. A fluid current motor comprising a supporting frame, a shaft carried by the frame, a motor frame comprising a pair of beams each pivotally mounted intermediate its ends upon said shaft and transverse shafts connecting the ends of said beams, a pair of sprocket wheels supported upon each of said transverse shafts, sprocket chains connecting the wheels on one of the transverse shafts with those on the other transverse shaft, arcuate arms secured at spaced intervals to each of said sprocket chains and extending inwardly thereof, a paddle pivotally mounted between the sprocket chains adjacent each of said arms, each paddle having slots therein to receive the adjacent arms, said arms maintaining the paddles in a plane extending transversely of the chains during a period of the operation of the motor, an open frame structure of substantially triangular cross-sectional design arranged between the chains adjacent each of said paddles, means for pivotally securing each frame at its ends to the adjacent chains in close proximity to the pivot point of the adjacent paddle, and a panel disposed within one of the two right angularly related sides of each frame, said frames when in one position acting to maintain the panels therein in a plane extending transversely of the chains to coact with the adjacent paddles during a period in the operation of the motor to receive the force of fluid current.
- In testimony whereof I hereunto affix my signature.
- JAMES S. RAGAINS.
